UNITED STATES PATENT OFFICE.

WILLIAM T. COATS, OF NEW ORLEANS, LOUISIANA.

LOCK PROTECTOR.

Application filed February 26, 1921. Serial No. 447,950.

To all whom it may concern:

Be it known that I, WILLIAM T. COATS, a citizen of the United States, residing at New Orleans, in the parish of Orleans and 5 State of Louisiana, have invented certain new and useful Improvements in Lock Protectors; and I do hereby declare the following to be a full, clear, and exact description of the invention, such as will enable others 10 skilled in the art to which it appertains to make and use the same.

The lock mechanism of safes, vaults and analogous depositories for valuables, documents and papers usually comprises a plurality of bolts, a bolt bar connecting the bolts for simultaneous operation thereof, and a lock device for securing the bolt bar in locking position.

When the usual lock device is actuated 20 and releases the bolt bar, the latter may be moved and the door of the safe, vault or other depository opened.

The present invention interposes an impediment to the movement of the bolt bar, thereby increasing the difficulty of unauthorized opening of the safe, vault and the like.

The invention consists of an auxiliary locking means adjunctive to the regular lock mechanism, whereby it becomes mandatory 30 that the auxiliary locking means be operated to release the bolt bar or analogous part of the main lock works before the latter can be actuated to release the door so that the latter may be opened.

Other objects and advantages will be apparent and suggest themselves as the nature of the invention is understood.

While the drawings illustrate an embodiment of the invention, it is to be understood 40 that in adapting the same to meet different conditions and requirements, various changes in the form, proportion and minor details of construction may be resorted to without departing from the nature of the 45 invention.

Referring to the accompanying drawings forming a part of the specification,

Figure 1 is an elevation of the inner side of a portion of a safe or vault door illustrative of the invention,

Figure 2 is a sectional detail of the auxiliary locking means showing the parts on a larger scale, and

Figure 3 is a further detail. 55 Corresponding and like parts are referred to in the following description and designated in the several views of the drawings by like reference characters.

The numeral 1 designates a door such as commonly provided for safes and vaults, 60 the same being equipped with the usual lock works embodying the ordinary bolt bar 2 which is operatively connected with all the bolts of the lock mechanism, whereby to effect simultaneous operation thereof. 65 The bolt bar 2 cooperates with the usual lock device 3, whereby the same is made secure against movement when the door is closed and locked.

The present invention provides locking 70 means for the bolt bar 2 independently of the usual lock device 3, whereby to add to the difficulty of unauthorized opening of the safe, vault or like depository. A lock device 4 is mounted upon the door 1 and may 75 be of any type, preferably consisting of the permutation variety. A rod 5 cooperates with the lock 4 and is controlled in its movements thereby. Telescoping members 6 and 7 are interposed between the bolt bar 80 2 and the door so as to prevent movement of the bolt bar when the door is locked. The member 7 is connected at one end to the bolt bar 2 and its opposite end telescopes with the member 6 which is made 85 fast at one end to the bolt frame 8, or other convenient part of the door. The member 6 is tubular and the member 7 is slidable therein. An elongated opening or slot 9 is formed in a side of the member 6 90 and a latch 10 is operable therethrough and cooperates with the parts 6 and 7 to prevent relative movement thereof in one direction, whereby to secure the bolt bar 2 and prevent movement thereof. The latch 95 10 is carried by the member 7, being pivoted thereto at 11 and adapted in one position to lie within the member 6 to admit of unobstructed movement of the member 7 so that the bolt bar 2 may be operated in 100 the usual manner to throw the bolt of the lock works and release the door after the lock 3 has been operated in the usual way. The weight of the latch 10 may be sufficient to throw the same into operative position. 105 However, to insure positive movement thereof a spring 12 is provided and is preferably attached at one end to the member 6, the opposite end cooperating with the latch 10. The member 7 is slotted to receive the latch 10 which is carried thereby.

When the door 1 is closed and locked, the

latch 10 of the auxiliary locking mechanism constituting the protector projects through the opening 9 of the member 6, thereby securing the member 7 and the bolt bar 2 connected therewith. Before the bolt bar 2 can be moved to effect opening of the safe, vault or like depository, the lock 4 must be actuated to effect release of the member 7. Should the bolt bar 2 be released from the lock 3 in any manner whatsoever, it cannot be moved without releasing it from the action of the auxiliary locking mechanism which is effected by movement of the rod 5 after the lock 4 has been operated. It will thus be understood that the invention interposes an impediment and further adds to the difficulty of surreptitious opening of the safe, vault or like part.

What is claimed is:

- 20 1. In combination with a bolt means for control through actuation of a lock, a barrel and a rod associated with said bolt means, said rod being slidable in said barrel, a latch on said rod, said barrel having a slot into which the latch extends, the latch in said position being adapted to abut a wall of said slot to function as a detent whereby unlocking movement of the lock

means is prevented, and lock-operable means to move said latch out of detaining relation with said barrel, the barrel wall serving to maintain the latch raised when disaligned with said slot.

2. In combination with a bolt means for control through actuation of a lock, a rod and a barrel associated with said bolt means, said rod being slidable in said barrel, said rod having a slot, a latch disposed within said slot and pivoted to the rod, said barrel having a slot to register with said slot, said latch being adapted to depend into the second slot and to abut a wall thereof to function as a detent, a sustaining spring for said latch on said barrel, a rod connected to and adapted to raise said latch out of detaining relation with said barrel, lock means to actuate the second mentioned rod, and the barrel wall serving to maintain the latch raised when disaligned with said slot of the barrel. 50

In testimony whereof I affix my signature in presence of two witnesses.

WILLIAM T. COATS.
